UNITED STATES PATENT OFFICE.

ALONZO D. SMITH, OF NEW WOODSTOCK, NEW YORK.

TRUSS-PAD.

SPECIFICATION forming part of Letters Patent No. 341,176, dated May 4, 1886.

Application filed November 19, 1885. Serial No. 183,341. (No model.)

To all whom it may concern:

Be it known that I, ALONZO D. SMITH, of New Woodstock, in the county of Madison and State of New York, have invented a new and useful Improvement in Truss-Pads, of which the following is a specification, reference being had to the annexed drawings, forming a part thereof, in which—

Figure 1 is a side elevation. Fig. 2 is a transverse section taken on line *xx* in Fig. 1. Fig. 3 is a rear elevation.

Similar letters of reference indicate corresponding parts in the different figures of the drawings.

15 The object of my invention is to provide a truss-pad for the prevention of intestinal protrusion through any of the abdominal walls.

My invention consists of the construction and arrangement of parts, as will be herein-20 after fully described and claimed.

The larger pad, A, is formed of wood or other suitable material, with an outwardly-convex face, *a*, and with a central aperture, *b*. A convex metallic plate, B, provided with a short cylindrical stem, *c*, is secured to the back of the pad A by means of ordinary steel screws, 25 or in any other suitable way.

In the aperture *b* of the pad A is inserted the hollow cylindrical stem C, having upon 30 its outer end the pad D. The pad D is smaller in diameter than the pad A, and its face is made outwardly convex.

Within the hollow stem C is placed a rubber spring, E, having formed on the opposite ends 35 thereof flanges *d* *d'*, the flange *d* closely fitting the interior of the hollow stem C, and the flange *d'* closely fitting the aperture *b* of the pad A and abutting upon the back plate, B, so that the rubber spring E not only acts as a

yielding support for the smaller pad, B, but it 40 also forms an efficient connector for holding the two pads A B in proper relation to each other. The stem C of the pad D fits the aperture *b* of the pad A closely, so that the pad D may move in or out without lateral move- 45 ment.

When applied to the patient, the smaller pad, D, is arranged opposite the hernial opening, while the larger pad, A, supports the abdominal walls around the opening.

The stem *c* is provided with a transverse opening for receiving the end of the wire F, which surrounds the body of the wearer of the truss, and the truss-pad is held in any desired position upon the wire by a binding-screw, *f*, 55 which is fitted in the stem *c* and bears upon the side of the wire F.

Although I have described the spring employed in my improved truss-pad as being made of rubber, I do not limit or confine myself to the use of a rubber spring, as a metallic spring of substantially the same form might be substituted therefor.

Having thus described my invention, what I claim as new, and desire to secure by Letters 65 Patent, is—

In a truss-pad, the combination, with the centrally-apertured pad A, of a smaller pad, D, provided with a tubular stem, C, closely fitted to the aperture of the pad A, and a 70 spring, E, having flanged ends, and arranged to connect the smaller and larger pads, substantially as herein specified.

ALONZO D. SMITH.
